(57) **CLAIM**

The ornamental design for a frame for operation button of elevator, as shown and described.

DESCRIPTION

FIG. 1 is a perspective view of front, right and top plan side of a frame for operation button of elevator showing our new design;

FIG. 2 is a front view thereof;

FIG. 3 is a rear view thereof;

FIG. 4 is a top plan view thereof;

FIG. 5 is a bottom view thereof;

FIG. 6 is a left side view thereof;

FIG. 7 is a right side view thereof;

FIG. 8 is an end view of cutting part at 8-8 in FIG. 2 omitting the interior mechanism; and,

FIG. 9 is a front reference view of usage.

The portions of the article in broken lines are shown for illustrative purposes only and form no part of the claimed design.
